UNITED STATES PATENT OFFICE.

WILLIAM LUMLEY, OF CHICAGO, ILLINOIS.

TEMPORARY BINDER.

SPECIFICATION forming part of Letters Patent No. 499,432, dated June 13, 1893.

Application filed December 29, 1891. Serial No. 416,450. (No model.)

To all whom it may concern:

Be it known that I, WILLIAM LUMLEY, a citizen of the United States, residing at Chicago, in the county of Cook and State of Illinois, 5 have invented certain new and useful Improvements in Temporary Binders, of which the following is a specification.

This invention relates to improvements in temporary binders for holding letter file indexes conveniently for the ready insertion of letters, bills and other documents during the continuous use of the file, and before the permanent storage of such matter.

The present invention is more especially 15 designed as an improvement on a device of this character covered by United States Letters Patent No. 532,537, granted to me July 22, 1890.

One of the objects of my invention is to 20 improve and greatly simplify the means for holding the impaling pin or bar which passes through the perforated tabs of the index sheets, securely in place, but with capability of being readily and quickly removed and 25 replaced without the necessity for manipulating any screws or slides or the like.

Another object of the invention is to provide a temporary binder with a simple and effective file holder for holding the papers and 30 index sheets down smooth and flat in the box or drawer, which shall consist of a minimum number of parts and be so constructed as to spring toward or from the papers after passing a certain point.

35 With these ends in view my invention consists in certain features of novelty hereinafter more fully described with reference to the accompanying drawings and more particularly pointed out in the claims.

40 In the said drawings, Figure 1 is a general perspective view of a file drawer or box provided with my improvements. Fig. 2, is a detail vertical sectional view taken on the line 2, 2, Fig. 1, on a larger scale. Fig. 3, is a 45 detail view showing the means for securing the impaling pin in position. Fig. 4, is a sectional plan view taken on the line 4, 4, Fig. 1. Figs. 5 and 6 are perspective views of modified forms of impaling pin hereinafter more 50 fully described.

In the drawings wherein like signs of reference refer to like parts throughout the sev-

eral views, A, is the box or drawer, and B, are the index sheets arranged therein and having the perforated holding tabs C, all of 55 the usual or any suitable and convenient form.

In carrying out the preferred form of my invention, I provide the front of the drawer or box in its inner side with a vertical or upright channel or groove D, of sufficient width and lateral depth to receive the attaching tabs C. This groove extends preferably from within a short distance of the top or upper edge of the drawer to a point slightly below the surface of the bottom of the drawer so as to form a 60 socket E, in said bottom. The groove D, may be of any desired contour and formed by any of the well known methods, as for instance by 65 gouging, routing or boring, but preferably by 70 boring, and as incidental to this preferred manner of making the groove or channel, it will of course be of semi-cylindrical contour, while the socket E, will be circular in form.

F, is the impaling pin or rod which passes 75 through the perforated tabs C, and thus holds the index sheets squarely in the box or drawer. This pin F, is preferably formed of a single piece of wire or spring metal having 80 near its upper end a thumb knob or handle G, formed by taking a turn or coil in the wire, which coil is preferably elliptical or flat so as to be as little as possible in the way of the 85 documents and index sheets when they are folded backward in the ordinary manner. Just above this thumb piece G, the wire terminates in a tenon H, which fits in a complementary socket or cavity h, preferably formed 90 in the portion of the drawer front just above the end of the bore or channel D, thus holding the upper end of the impaling pin in position.

When it is desired to slip the index sheets upon or remove them from the impaling pin, the tenon H, may be inserted through their 95 perforated tabs C, and the pin then turned through the hole after the manner of an ordinary screw spiral, the pin in every instance being provided at its lower end with suitable means for preventing the tabs from slipping 100 therefrom.

The tenon H, on the impaling pin is held upward in its socket h, by means of a spring of any convenient and suitable form. I pre-

fer, however, to employ as an effective and inexpensive arrangement, a spring formed integrally with the pin itself, thus at the same time providing the pin with a stop or button 5 for preventing the tabs from slipping off at the lower end of the pin. This preferred form of spring is made by simply taking a spiral turn or coil I, in the lower end of the wire of which the pin is formed, which coil 10 also constitutes a foot which fits in the socket E, and is preferably of the same, or substantially the same diameter as said socket, so that the pin will be held firmly against lateral displacement or movement at its lower 15 end.

When it is desired to remove the index sheets from the impaling pin for any purpose, a slight downward pressure is applied to the thumb piece G, so as to disengage the tenon 20 H, from its socket, whereupon the pin may be drawn outward and lifted from the socket E. The coil G, not only serves as a handle or knob with which to manipulate the pin, but constitutes a top stop for preventing the tabs 25 from slipping off at the top of the pin when the end of the latter is out of its socket h. As a modification of this arrangement, the spring and foot at the lower end of the impaling pin may be formed separately of a bow or blade 30 spring I' secured to the end of the pin in any suitable way as shown in Fig. 5. In this instance, however, the socket for the reception of the spring foot will be formed by cutting transverse sockets E', on both sides of the 35 bore D, below the surface of the bottom of the drawer. And as a modification of this blade spring, the end of the wire of which the impaling pin is formed, may be bent at an angle so as to form a spring piece I², and a foot rest 40 I³, and if desired such bent portion flattened as shown in Fig. 6.

K, is the holder which I have herein termed a file holder, for holding or compressing the papers and index sheets in the drawer so as 45 to prevent their free edges from curling up and interfering with the drawer being pushed into the usual cabinet. This holder consists preferably of a single piece of wire or other strip bent into a suitable form best adapted 50 for bearing upon the papers, whose arms k, are each provided near their extremities with a portion bent at an angle thereto, and forming journals k' journaled in loops L, secured on the inner side of the front of the drawer 55 by means of screws M, entering shoulders formed on the front portion of the drawer,—the said portion of the drawer being cut away as shown and the journals let in flush with the surface thereof. The said journals k', 60 terminate in short cranks or cams K², which project outwardly and are provided with beveled or rounded ends which are adapted to impinge against the inner side of a stout blade spring N, respectively near the ends of the 65 latter, and thus cause the holder to spring up or down according as the points of contact be-

tween the spring N, and the cranks K², are above or below the center of bearing of the ends of said cranks. Thus if the holder is pushed down until the spring bears on the upper sides or bevels of the cranks, the pressure of the spring will continue such downward movement; and on the other hand, if the holder is elevated until the lower sides of the cranks begin to receive pressure from the 70 spring, the holder will be thrown into a vertical position, and there held. This spring N, is preferably formed in one piece and let in flush with the end of the drawer to which it is secured by means of screws O. But obviously such spring might be formed in two pieces if desired, without departing from the spirit of my invention.

A temporary binder thus constructed is simple and durable, and consists of but a 85 minimum number of parts with no frail or complicated mechanism liable to break or become deranged, or to interfere with the free use of the device.

Having described my invention, what I 90 claim, and desire to secure by Letters Patent, is—

1. In a temporary binder, the combination with the drawer having a socket, of a removable impaling pin having a spring foot or 95 guard formed integrally therewith for holding the upper end of said pin in said socket, substantially as set forth.

2. In a temporary binder, the combination with the drawer having a socket; of an impaling pin having a thumb piece formed thereon near its upper end and a spring for holding said pin in said socket, substantially as set forth.

3. In a temporary binder, the combination 105 with the drawer having a socket near its upper edge; of a removable impaling pin having a spring foot or guard adapted to hold the upper end of said pin in said socket, substantially as set forth.

4. In a temporary binder, the combination 110 with the drawer having an upright groove or channel formed in the side thereof, provided with sockets at its upper and lower ends; of an impaling pin having a spring foot fitting 115 in the lower one of said sockets and a tenon resting in the upper one of said sockets, substantially as set forth.

5. In a temporary binder, the combination 120 with the drawer having an upright groove or channel formed in the side thereof, provided with sockets at its upper and lower ends; of an impaling pin having a spring foot fitting in the lower, and a tenon fitting in the upper of said sockets, said pin being provided with 125 a thumb piece, substantially as set forth.

6. In a temporary binder, the combination 130 with the drawer having a groove or channel formed therein, and provided with sockets at its upper and lower ends; of an impaling pin, a coil formed integrally with said pin at its lower end fitting in said lower socket, a turn

or coil formed in said pin near its upper end and terminating in a tenon fitting in said upper socket, substantially as set forth.

7. In a temporary binder, the combination with a drawer, of a file holder consisting of a frame, having two arms terminating in cranks or cams journaled to the side of the drawer, and a flat spring secured between its ends to the side of the drawer and having two free ends bearing upon said cranks respectively, substantially as set forth.

8. In a temporary binder, the combination with the drawer; of the file holder consisting of an integral frame, having two arms journaled to the side of the drawer, a crank or cam for operating said frame, and a flat spring let into a recess in the front of the drawer, secured to said drawer and having a free end bearing upon said crank, substantially as set forth.

9. In a temporary binder, the combination with the drawer; of a frame having two arms provided at their extremities with journals, k' , journaled to the side of the drawer and terminating in cams K^2 , and a flat spring secured to the side of the drawer and bearing upon said cams K^2 , substantially as set forth. 25

10. In a temporary binder, the combination with a drawer having recesses in one side thereof; of a frame having two arms, provided at their extremities with journals, k' , journaled in said recesses and terminating in cams K^2 projecting from said recesses, and a flat spring secured between its ends to the side of said drawer, and bearing upon said 30 cams K^2 , substantially as set forth. 35
